UNITED STATES PATENT OFFICE

FRIDOLF FRANKEL, OF STOCKHOLM, SWEDEN

SOUND DEVICE FOR STRINGED INSTRUMENTS

Application filed July 14, 1927, Serial No. 205,738, and in Germany October 12, 1926.

Sound boards for stringed instruments, such as for instance pianos, piano-fortes and the like, have hitherto been made from a wooden plate (clean spruce), which has been 5 planed off to a thickness of about 10 mm. at the treble portion and of about 6 mm. at the base portion. Glued to the said plate is a number of transverse, crookedly planed ribs adapted to strengthen particularly the inner 10 portions of the plate.

At the edge portions of the plate, the said ribs have been reduced from their original thickness of about 30 mm. to a thickness of about 4 mm. only along a length of about 15 150 mm. from the edges of the plate. For the said reduced end portions of the ribs recesses have been made in the rear frame, and the plate has been directly glued to the said frame in order that the edges of the 20 plate may be firmly secured and thus the plate be capable of taking up the stress from the string pressure, which has to be carried wholly or to the greatest extent by the plate.

In order to increase the bearing capacity 25 of the said plate, particularly at the middle portions thereof, the plate was carefully dried and contracted and then the somewhat curved ribs or lists were glued on. When the plate was then subjected to the moisture of the air 30 it swelled and made the previously curved lists still more curved, so that the whole plate was curved. In such a state the plate was glued to the frame of the instrument. However, the sounding capacity of such a plate 35 was very limited, and a powerful, singing and noble tone cannot be obtained.

The present invention relates to a new sounding system for stringed instruments, whereby the musical value of the instrument 40 will be considerably increased.

The sounding system according to the invention consists of a plurality of vibration beams which are with their ends very firmly secured to the frame of the instrument and 45 which are of such a construction and strength as to be able to carry the bridges and the whole string pressure or a part, preferably a considerable part thereof. The said beams may preferably consist of two or more parts 50 glued to each other in the longitudinal direc-

tion, preferably when in a curved state so as to obtain an interior tension, which considerably increases the vibration capacity. The ends of the said beams are not reduced, as heretofore, to a thickness of about 4 mm. but 55 are made with a thickness of at least 10, preferably 15 or 20 mm., in order that they may be sufficiently strong and capable of being reliably secured to the frame. In some cases the beams may be of equal thickness 60 throughout their length, i. e. the ends thereof will not be reduced, or the ends may be thicker than the middle portion.

A thin sounding or vibration plate may, 65 if desired, be glued to the said beams, and said plate may be made of such a size as not to reach to the frame of the instrument, in which case the beams have to carry the whole string pressure, the plate being wholly relieved from such pressure. However, the 70 said plate may, if desired, extend to the frame of the instrument at some or more places and be glued thereto, so as to carry part of the string pressure, said part being at most 75% 75 of the total string pressure, while the resulting part (thus at least 25% of the pressure) will be carried by the vibration beams. However, the total string pressure may in this case preferably be divided in such way that the beams take up about 60 to 80% of said 80 pressure, while the remaining 40 or 20%, respectively, of the pressure will be carried by the vibration plate.

In a sounding device according to this invention, where the vibration beams carry the 85 main part of the string pressure and where the sounding plate secured thereto constitutes merely an appendix adapted to give the tone a certain character, but where the vibration beams form a powerful connection with the frame of the gear, the conditions will be such that the vibrations of the strings are transmitted through the bridges and the vibration plate to the vibration beams and extend along 90 said beams until they are resisted by the frame of the instrument.

If now the end portions of the vibration beams are strong and firmly secured to the frame, a violent conflict will arise between 95 the vibrating part of the beams and the se- 100

cured part thereof. The latter part does not permit the vibrations to pass further on but resists them and sends them back and thus increases the vibrations and prolongs the time thereof. It has also been proved that, first when the vibrations are subjected to the resistance from the frame, they will become the capacity of intensifying the tone and giving it the right character.

10 In the annexed drawings some forms of embodiment of a sounding device according to the one form of embodiment to the present invention are shown. Fig. 1 is a front elevation of a sounding device according to the one form of embodiment. Fig. 2 is a transverse section of part of said device along line 2—2 of Fig. 1 on an enlarged scale. Fig. 3 is a front elevation of a somewhat modified sounding device. Fig. 3^a is a sectional view on line 3^a—3^a of Fig. 3. Figs. 4 and 5 are transverse sections of sounding devices according to further modifications.

Referring first to Figs. 1 and 2 of the drawing, *a* represents the rear frame of the instrument, to which is secured a number of vibration beams *b*, the ends of which are reduced to about half the thickness of the beam proper, as visible from Fig. 2. As mentioned, the thickness of the said reduced ends ought to be at least 10 mm., preferably about 15 to 20 mm., in order to obtain the required steadiness. Applied to the fore side of the said beams *b* is a vibration plate *c*, the edges of which are glued to the beams *b* and which does not extend to the frame *a*, except at two diagonally opposed corners, as shown in Fig. 1, the plate *c* being glued to the frame *a* at said corners. If desired, the plate *c* may extend to and be glued to the frame *a* also at other places, so as to assist the beams *b* in carrying the string pressures to a greater or less degree. As previously mentioned, the plate *c* ought to carry at most 75% of the total string pressure, or preferably not more than 50% of said pressure, the remaining and preferably greater part being carried by the vibration beams *b*. The plate *c* may, if desired, not at all extend to the frame *a*, i. e. be wholly carried by the beams *b*, in which case the latter will have to carry the whole string pressure. Inserted into the plate *c* are vibration intensifying fillets or plat-bands *f* made from harder wood than the plate proper, the bridges *d* adapted to carry the strings in the usual way being secured to said fillets. By such means, the vibrations from the bridges to the vibration beams *b* will be more powerful and transmitted in a more convenient manner, so that the sounding possibilities will be better utilized.

In the form of embodiment shown in Fig. 3, the vibration plate *c* is secured to the back of the beam system *b*. By such means a more powerful and noble tone will be ob-

tained, inasmuch as the tone will be better the greater the distance is between the strings and the plate. Besides, the bridges *d* are in this case carried by transverse plat-bands *e* extending to the frame *a* and glued thereto so as to prevent displacing of the bridges *d*. As shown, the plate *c* does not at all extend to the frame *a*, the string pressure being wholly carried by the beams *b* which may be reduced at the ends and secured to the frame by gluing in the manner shown in Fig. 2.

According to the modification shown in Fig. 4, the vibration beam *b* is of the same thickness throughout its length, the ends thereof, which are secured into recesses in the frame *a* by gluing, being not at all reduced. The beam *b* consists in this case of two parts glued to each other in the longitudinal direction, as indicated by the line *l*. In this case the two parts may preferably consist of wood having a different degree of hardness and elasticity.

In the modification shown in Fig. 5, the ends of the vibration beam *b* are thicker than the middle portion thereof, it being held in mind that the thickness of the said ends must not be less than hereinbefore set forth.

A beam system according to the invention, particularly such a system having a sounding plate, has a considerably better vibration capacity than the ordinary sounding boards. By the increase of the vibration capacity the tone will be intensified and thus more powerful and noble.

What I claim as new and desire to secure by Letters Patent of the United States of America is:—

1. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof.

2. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, and a vibration plate being secured to said vibration beams.

3. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, a vibra-

- tion plate being secured to said vibration beams and also to said frame so as to assist the said beams in carrying the string pressure.
4. A stringed instrument according to claim 3, characterized by the vibration plate carrying at most 75% of the string pressure.
5. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, said beams being of about the same thickness throughout their length.
- 10 6. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, a vibration plate being secured to said vibration beams at the rear side thereof.
- 15 7. A stringed instrument according to claim 5, characterized by the bridges being secured to plat-bands connected to the frame of the instrument.
8. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, a vibration plate being secured to said vibration beams, said vibration plate being secured with its edges to said vibration beams.
- 20 9. A stringed instrument according to claim 5, characterized by the bridges being secured to plat-bands connected to the frame of the instrument.
- 25 10. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, a vibration plate being secured to said vibration beams, said vibration plate being provided with vibration intensifying fillets made from a harder material than the plate proper, the bridges being secured to said fillets.
- 30 11. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, said beams being of about the same thickness throughout their length.
- 35 12. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, a vibration plate being secured to said vibration beams, said beams being of about the same thickness throughout their length.
- 40 13. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, said beams consisting each of at least two longitudinal parts glued to each other when in a curved state and being of about the same thickness throughout their length.
- 45 14. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, a vibration plate being secured to said vibration beams, said beams consisting each of at least two longitudinal parts glued to each other when in a curved state and being of about the same thickness throughout their length.
- 50 15. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, said beams consisting each of at least two longitudinal parts glued to each other when in a curved state, said separate parts of the vibration beams consisting of wood having a different degree of hardness and elasticity.
- 55 16. A stringed instrument comprising a frame, a sounding system carried by said frame and bridges for the strings of the instrument carried by said sounding system, said latter system comprising a plurality of vibration beams secured at their ends to said frame and serving to carry the string pressure or a considerable part thereof, a vibration plate being secured to said vibration beams, said beams consisting each of at least two longitudinal parts glued to each other when in a curved state.
- 60 65

frame and serving to carry the string pressure or a considerable part thereof, a vibration plate being secured to said vibration beams, said beams consisting each of at least two longitudinal parts glued to each other when in a curved state, said separate parts of the vibration beams consisting of wood having a different degree of hardness and elasticity.

10 In testimony whereof I affix my signature.
